UNITED STATES PATENT OFFICE

118,162

DESIGN FOR A ROLLED METAL BAR

Francis M. Lambert, Narberth, Pa.

Application October 17, 1939, Serial No. 87,704

Term of patent 14 years

To all whom it may concern:

Be it known that I, Francis M. Lambert, being a citizen of the United States and a resident of Narberth, in the county of Montgomery and Commonwealth of Pennsylvania, have invented a new, original, and ornamental design for a Rolled Metal Bar, of which the following is a specification, reference being had to the accompanying drawing, forming a part thereof, in which:

Fig. 1 is a perspective view of one side of the rolled metal bar embodying my new design; and

Fig. 2 is a perspective view of the reverse side of the rolled metal bar.

The essential features of my design reside in a rolled metal bar of the configuration shown, the same consisting of two intersecting flanges presenting two plane surfaces intersecting at right

angles as viewed in Fig. 1. When viewed endwise as illustrated in both figures, the shape presents a thickened or bulbous edge portion projecting inward away from one of the two plane surfaces, extending lengthwise and defining the edge of said plane surface. The shape also presents an intermediate enlarged rib portion likewise projecting away from the above-mentioned plane surface and parallel to the bulbous portion. On the side opposite the two intersecting plane surfaces above-mentioned, the intersection of the two flanges presents a rounded surface.

What I claim is:

The ornamental design for a rolled metal bar, substantially as shown and described.

FRANCIS M. LAMBERT.
